(57) **CLAIM**

The ornamental design for a task chair, as shown and described.

DESCRIPTION

FIG. 1 is a perspective view of a task chair;
FIG. 2 is a right side view of the task chair shown in FIG. 1;

FIG. 3 is a front view of the task chair shown in FIG. 1;
FIG. 4 is a left side view of the task chair shown in FIG. 1;
FIG. 5 is a rear view of the task chair shown in FIG. 1;
FIG. 6 is a top view of the task chair shown in FIG. 1; and,
FIG. 7 is a bottom view of the task chair shown in FIG. 1.
The broken lines showing a lumbar support in FIGS. 1, 2, 3,
4, 5 and 7 are for environmental purposes only and do not
form any part of the claimed design.

1 Claim, 4 Drawing Sheets
